UNITED STATES PATENT OFFICE

136,108

DESIGN FOR A WEATHER INDICATING DEVICE

Clyde Casey, Detroit, Mich.

Application February 15, 1943, Serial No. 109,550

Term of patent 7 years

To all whom it may concern:

Be it known that I, Clyde Casey, a citizen of the United States, residing in the city of Detroit, county of Wayne, and State of Michigan, have invented a new, original, and ornamental Design for Weather Indicating Devices, of which the following is a specification, reference being had to the accompanying drawing, forming part thereof.

Fig. 1 is a front elevational view of a weather indicating device showing my new design;

Fig. 2 is a side elevational view; and

Fig. 3 is a perspective view thereof.

I claim:

The ornamental design for a weather indicating device, as shown.

CLYDE CASEY.
